UNITED STATES PATENT OFFICE.

WILLIAM H. RUTTLE, OF SEATTLE, WASHINGTON.

BUTTER-CUTTER.

1,331,786.

Specification of Letters Patent. Patented Feb. 24, 1920.

Application filed October 14, 1919. Serial No. 330,641.

To all whom it may concern:

Be it known that I, WILLIAM H. RUTTLE, a citizen of the United States, and resident of the city of Seattle, county of King, and State 5 of Washington, have invented certain new and useful Improvements in Butter-Cutters, of which the following is a specification.

My invention relates to butter cutters, and comprises a device which may be used to divide a pat or cake of butter into a number of small chips for table use by pressing cutting wires through the cake.

The object of my invention is to provide a cutting means of the sort described which 10 is composed of a number of wires, and to provide means for tightening and for keeping tight all of the wires used in this cutter.

My invention comprises the novel parts and combinations thereof which are shown 15 in the accompanying drawings, described in the specification, and particularly defined by the claim terminating the same.

In the accompanying drawings I have shown my invention in its present preferred 20 form.

Figure 1 is a plan view of my device.

Fig. 2 is a transverse sectional view of the device.

Fig. 3 is a detail in section of the means 30 for holding and tightening an end of one of the wires.

In devices of this character it is essential that all of the wires be kept tight. Preferably they should be kept at a nearly uniform 35 tension throughout the device. If the wires become loose, poor work results, and breakage of the wires. It is necessary, also, to produce a device which is simple to adjust, and one in which new wires may be quickly 40 and easily put in place in the event of breakage. These objects are accomplished with the use of my device.

Any suitable frame may be used in this device. The frame herein shown is intended 45 for manual operation. The frame 1 is provided with a rectangular opening 10, which is of a size to fit over an ordinary cake of butter, as sold commercially. The size and shape of the opening 10 may be varied to 50 suit the desires and needs of the trade. Along two opposite sides of the opening 10, and as herein shown along all four sides of the opening, are raised ridges 11. These ridges are adapted to form the supports for series 55 of cutting wires. The wires 2 are held at their ends by means to be hereinafter de-

scribed. They are passed back and forth across the opening 10 from side to side, and are held upon pins 12 along the edge of the frame 1. As is shown in the drawings, the 60 wires pass over the ridge 11 and are preferably guided and held in place thereon by shallow transverse grooves 13 in the ridge 11. A similar wire 20 may extend lengthwise of the opening 10, being secured at one 65 end upon a pin 14, and at its other end by means to be later described, and passing over the end ridge 11.

In order to tighten the ends of the wires, these are secured in a slot 41 in the end of 70 screws 4. These screws are threaded in the frame and have their ends projected upward therefrom a considerable distance. The slot 41 extends part way down to the frame and in these slots the ends of the wires 2 or 20 75 are placed. They may be secured therein by pinching together the sides of the slots, thus clamping the wire ends in place. The wire is then tightened by turning the screw, when the wire will lie in the bottom of the 80 threads, and will be securely held thereby. As the wire winds about the screw it is tightened, and when adjusted to the proper tension may be held by means of a lock nut 42 upon the screw 4 at the side of the frame 85 opposite to the slot 41.

While the initial tension upon the wires is secured in the manner described, this results in an inequality of tension between the ends of the wires and their centers. To overcome 90 this, I provide ridges 15 substantially parallel to the ridges 11, along the longitudinal sides of the openings 10, over which the wires pass. The wires then form a bridge across the trough between the two ridges 11 95 and 15. Upon these portions of the wires, and extending longitudinally between the two ridges, I place a bridge bar or tension member 5. This bar I prefer to form as semi-circular in cross section. It contacts 100 with all of the wires that pass across the two ridges 11 and 15. A number of screws 51 which screw into the frame are provided to clamp this bridge bar 5 to the frame. Thus when the initial tension has been placed 105 upon the wires 2, a further tension may be placed upon the wires between their ends by clamping this bridge bar 5 in place. This produces an even tension upon all of the wires, and by occasionally tightening the 110 screw 51 the wires 2 may be kept at all times tight in the frame and under an even ten-

sion. This produces a more efficient cutting machine and prevents breakage of the wires, which is very apt to occur if the wires become loosened.

5 A series of grooves 13 may be provided upon ridges 11 at each side of the frame. These may differ in number upon each side, so that a variation may be made in each frame of the number of chips to be cut from 10 a cake of butter.

While I have shown but one wire extending across the opening many times, it is evident that any number desired may be used. Single wires only may be stretched from side 15 to side, but I prefer to use one wire only, on account of the ease in adjusting it and tightening it upon the frame. The cost of the device is lessened, also, by reducing the number of screws and lock nuts required.

What I claim as my invention is:

A butter cutter comprising a frame having an opening therein to receive a cake of butter, a pair of ridges upon the frame adjacent a side of said opening, means carried by said frame for attaching wires thereto, a wire extending back and forth across said opening and over said ridges, means for securing the ends of said wire in the frame, oppositely disposed bridge bars lying upon and contacting with said wires between said ridges, and means for clamping said bridge bars to the frame, whereby the tension applied to the wires in the ridges of initial contact and the strain are removed from the attaching means. 20 25 30 35

Signed at Seattle, Washington, this 8th day of October, 1919.

WILLIAM H. RUTTLE
